POCKET CLIP

Nolan Kent Rhoades, Milton, Wis., assignor to The Parker Pen Company, Janesville, Wis., a corporation of Wisconsin

Application May 7, 1952, Serial No. 19,623

Term of patent 14 years

(Cl. D74—1)

To all whom it may concern:

Be it known that I, Nolan Kent Rhoades, a citizen of the United States, residing at Milton, county of Rock, State of Wisconsin, have invented a new, original, and ornamental Design for a Pocket Clip, of which the following is a specification, reference being had to the accompanying drawing, forming a part hereof.

In the drawing:

Fig. 1 is a front elevational view of a pocket clip, embodying my new design;

Fig. 2 is a side elevational view of the pocket clip;

Fig. 3 is a perspective view thereof; and

Figs. 4, 5 and 6 are cross-sections of the pocket clip taken on the lines 4—4, 5—5 and 6—6, respectively, of Fig. 1.

I claim:

The ornamental design for a pocket clip, as shown.

NOLAN KENT RHOADES.
